DEVICE FOR THE TRANSMISSION OF CALLING AND CLEARING SIGNALS IN LONG DISTANCE TELEPHONIC CIRCUITS

Myron Lebedinsky, Montlucon, France, assignor to Societe Anonyme de Telecommunications, Paris, France, a corporation of France

Application December 29, 1945, Serial No. 638,108
In France April 22, 1943

9 Claims. (Cl. 179—84)

1

The present invention pertains to a device for the transmission of calling and clearing signals in long distance telephonic circuits. These signals are generally transmitted in circuits of this kind by means of alternating currents having a frequency comprised in the band of frequencies used for conversation or call currents, so that the signalling currents behave, in the circuits, in the same manner as the call currents. For example, it is the custom to make use, for calling signals, of currents of 500 periods per second and, for clearing signals, of periodical currents, at 500/20, produced by a current generator at 500 P./S. the circuit of which is interrupted and then closed again 20 times per second. At the ends of the circuits, use is made of apparatus called voice-frequency ringers on two-wire circuits, or termination sets on four-wire circuits, the object of which is: on the one hand, to transform the signalling currents of voice frequency into currents adapted to operate the corresponding receivers at the telephone exchanges, that is, alternating current of low frequency or continuous current; on the other hand, to transform a signal emitted by the telephone exchange in the form of a low frequency current into a 500/20 current to be transmitted by the circuit.

In known devices of this type, the sending of the calling and clearing signals is carried out by means of suitable generators which are connected to the telephonic circuits, said connection being effected in such a manner that the call circuit is at the moment interrupted. This device however has the drawback that the call currents meet, on their path, relay contacts the quality of which may become insufficient by reason of the interposition of dust particles or of insulating particles which are in suspension in the air and which may deposit, in the course of time, on the circuit breaking contacts during their operation.

The purpose of the device forming the object of the present invention is to allow the retransmission of the calls without necessitating the use of relay contacts in the telephonic circuits, and it is characterised by the fact that it comprises means for connecting the generators of the calling and clearing signals in parallel on the telephonic circuits so as not to cause the latter to be cut off.

According to a form of embodiment of the invention, this device comprises the elements enabling a four-wire circuit to be transformed into a two-wire circuit in a manner known per se, as well as a group of relays enabling, on the

2

one hand, a low frequency current generator (25 P./S.) to be connected in parallel across this two-wire circuit at the time of sending towards the exchange through the incoming pair of a signal of voice frequency modulated at low frequency (500/20) and, on the other hand, a generator of current of voice frequency to be connected in parallel across the outgoing pair of the four-wire circuit at the time of sending through the two-wire connecting circuit of the trunk exchange a low frequency current, the connections from the said generators to the circuits being carried out without interruption of the latter.

By way of example, a form of embodiment of a four-wire termination and signalling set in accordance with the invention is described hereafter and is illustrated in the accompanying drawing.

This drawing shows diagrammatically the incoming end to a trunk exchange of a four-wire telephone circuit comprising the incoming pair 1 for the call currents proceeding towards this exchange, as well as the outgoing pair 2 for the call current proceeding from the exchange. In accordance with the invention, the termination and signalling set comprises, in the first place, means known per se, for transforming the four-wire circuit 1, 2 into a two-wire circuit 3 connected to the trunk exchange. These means comprise a differential transformer 4 having three windings: the line 1 is connected to the terminals of the winding 5, whilst the line 2 is connected, by means of a transformer 6, to the mid-points of the other windings 7 and 8 of the differential transformer, the ends of these windings 7 and 8 being connected on the one hand to the circuit 3 and, on the other hand to a balancing network 9.

On the incoming line, before a filter 10, are branched leads for connecting to said line an amplifier 11 for amplifying the calling and clearing currents. This amplifier receives current at 500/20 and actuates two relays 12 and 13, the effect of which, when their respective armatures 14 and 15 are in their operative position, is to allow a relay 16 to come to the position of rest, the armature 17 of which in its turn brings to the position of rest a relay 18 the armature of which closes the circuit of a relay 20. The relay 18 comprises two other armatures, one of which 21 causes, when relay 16 is in the operative position, the circuit of a relay 22 to close, the armatures of the latter 23, 23' controlling the connection between the amplifier 11 and the line 1. The relay 20, which is energized in the manner ex-

plained above at the time a signalling current is sent in line 1, comprises two armatures 24, 24' respectively connected to the two leads of the two-wire circuit 3 and movable between two pairs of contacts 27, 27'-28, 28' respectively connected to a line relay 25 and to the circuit 26 of a low frequency current generator (25 P./S.). The energizing of the relay 20 causes the line relay 25 to be disconnected from the line 3 and the circuit 26 of the generator to be connected to said line. This generator thus becomes branched to the line without the latter being sectioned. At the same time, through its armature 51, the relay 20 actuates the relay 42, which, by means of its armatures 43 and 43', controls the connection between the line 1 and the differential transformer 4; this connection is then interrupted, and the pair 1 is connected to the pair 3' used for through calls. The armature 45 of the relay 42 closes the filter on a resistance 46 to ensure adaptation of the impedance. Likewise, the resistance 47, put in circuit by means of the armature 48 of a relay 49 fed by the lead 50, has for its object to ensure adaptation of the impedance.

A portion of the current at 25 M./S. coming from the circuit 26 of the generator is sent through the two-wire line 3 towards the trunk exchange, where this current causes the signalling apparatus to operate; the other portion of this current, which is transmitted through the two-wire line 3 in the opposite direction to that of the exchange, is sent towards the outgoing circuit 2, but this current is, on the one hand, very much weakened by a condenser 29 mounted in series in the two-wire circuit 3 and, on the other hand, this current at 25 P./S. is not transmitted by the cable and the telephonic repeater parts, so that this portion of the current which is not used for controlling the signalling apparatus of the exchange, has no detrimental effect. Moreover, due to the operation of the relay 42 which has connected the pair 1 to the pair 3', the current at 25 P./S. cannot reach the amplifier 11.

In the case where the signal at 500/20 has to be sent from the trunk exchange into the outgoing circuit 2, a 500/20 current generator 30 is connected to said circuit through the medium of a potentiometer 31, by means of the armatures 32, 32' of the relay 22, the contacts of these armatures being permanently connected respectively to two leads of the circuit 2. The armature 32'' of the relay 22 forms a short-circuit behind the artificial line 51, thereby preventing the current at 25 P./S. sent by the exchange from mixing with the voice frequency current emitted by the signalling set. The operation of the relay 22 controlling the connection between the generator 30 and the circuit 2 is obtained as follows: a current having a frequency of 25 P./S. is sent from the trunk exchange into the two-wire circuit 3. Through the resting contacts 27, 27' of the armatures 24, 24' of the relay 20, this current is sent through the winding of the relay 25 the armature 33 of which closes the circuit of the relay 22, said circuit being already closed by the armature 21 of the relay 18 which is then at that moment in the operative position. The effect of the operation of the relay 22 is, on the one hand, to apply the armatures 32, 32' of this relay on their contacts and thus to connect the generator 30 with line 2, and, on the other hand, to disconnect, by attraction of the armatures 23, 23' of this same relay, the amplifier 11 from the circuit 1. In this manner, the relays 12, 13, 16 and 18 can no longer be actuated by a signal com-

ing through the line 1 which is thus prevented from disturbing the sending of the signal through the circuit 2. Moreover, the armatures 14 and 15 of the relays 12 and 13 open, in their resting position, the circuit of a relay 16 which controls a relay 18 the armature 19 of which opens, in its operative position, the lead 36 feeding the relay 20. The relays 18 and 16 therefore play the part of locking relays preventing, during the sending or the reception of a signal, any interference which might be caused by a signal of opposite direction.

This device may also be used for ensuring the transmission of a signal constituted by a non-modulated current at 500 P./S. arriving through circuit 1, the reception of this signal being manifested by applying, to the leads of the two-wire circuit 3, the negative pole of a battery 37 the positive pole of which is connected to earth; this connexion is obtained by means of the lead 38 controlled by the armatures 39 and 40 of the relays 18 and 34 and connected to the mid-point of a winding 41 mounted in parallel on the circuit 3. Contact 40 of the relay 34 which is moved to its working position when the relay is energized closes the circuit 38. The contact 39 of the relay 18 opens the circuit 38 when the relay 16 is deenergized, i. e., when no signal is received through the incoming pair 1.

30 What I claim is:

1. A device for the transmission of voice frequency calling and clearing signals in long distance four-wire telephonic circuits comprising an auxiliary two-wire circuit connected to the trunk exchange, means for connecting said two-wire circuit to the four-wire circuit, a low frequency current generator, a generator of voice-frequency signals modulated at low frequency, a relay circuit, means actuated by said relay circuit for connecting said low frequency current generator in parallel with said auxiliary two-wire circuit, means connected to the incoming pair of the four-wire circuit for energizing said relay circuit when receiving a voice frequency signal through said incoming pair, and means actuated by said relay circuit for connecting said generator of voice frequency signals in parallel with the outgoing pair of the four-wire circuit.

2. A device as claimed in claim 1, wherein said means for connecting said auxiliary two-wire circuit to the four-wire circuit comprises a differential transformer.

3. A device as claimed in claim 1, including a filter connected across the incoming pair of the four-wire circuit, said relay circuit energizing means including a voice-frequency current amplifier connected across the incoming pair ahead of said filter, and a chain of relays actuated by said amplifier, a line relay, the arrangement of 55 said relay circuit actuated means being such that the last relay in said relay circuit disconnects said line relay from said auxiliary two-wire circuit and connects said low frequency generator in parallel with said circuit.

65 4. A device as claimed in claim 1, wherein said means for connecting said auxiliary two-wire circuit to the four-wire circuit comprises a differential transformer including a filter connected across the incoming pair of the four-wire circuit, 70 said relay circuit energizing means including a voice-frequency current amplifier connected across the incoming pair ahead of said filter, and a chain of relays actuated by said amplifier, a line relay, the arrangement of said relay circuit actuated means being such that the last relay in

said relay circuit disconnects said line relay from said auxiliary two-wire circuit and connects said low frequency generator in parallel with said circuit, a special pair for transmitting through calls connected to the incoming pair, a relay for preventing that part of the low frequency current that is not transmitted to the exchange from being applied to said amplifier, and means for controlling said last mentioned relay from said last relay in said relay circuit, said relay thus controlled by said last relay of said relay circuit controlling the connection between the incoming pair and said differential transformer and the connection between the incoming pair and said special pair.

5. A device as claimed in claim 1 including a filter connected across the incoming pair of the four-wire circuit, said relay circuit energizing means including a voice-frequency current amplifier connected across the incoming pair ahead of said filter and a chain of relays actuated by said amplifier, a line relay, the arrangement of said relay circuit actuated means being such that the last relay in said relay circuit disconnects said line relay from said auxiliary two-wire circuit and connects said low frequency generator in parallel with said circuit, said means for connecting said auxiliary two-wire circuit to the four-wire circuit comprising a differential transformer, a relay actuated by said line relay, means including said last named relay for connecting said generator of voice-frequency signals modulated at low frequency to the outgoing pair of the four-wire circuit behind said differential transformer.

6. A device as claimed in claim 1 wherein said means for connecting said auxiliary two-wire circuit to the four-wire circuit comprises a differential transformer, and including a filter connected across the incoming pair of the four-wire circuit, said relay circuit energizing means including a voice-frequency current amplifier connected across the incoming pair ahead of said filter and a chain of relays actuated by said amplifier, a line relay, the arrangement of said relay circuit actuated means being such that the last relay in said relay circuit disconnects said line relay from said auxiliary two-wire circuit and connects said low frequency generator in parallel with said circuit, a transformer connecting the outgoing pair of the four-wire circuit to said differential transformer, said line relay being energized by being connected to said auxiliary two-wire circuit when said last relay in said relay circuit is at rest, a relay actuated by said line relay, means including said last mentioned relay for connecting said generator of voice-frequency signals modulated at low frequency to the outgoing pair of the four-wire circuit behind the transformer connecting said outgoing pair of said differential transformer, said last mentioned relay being provided with an auxiliary contact for short-circuiting said outgoing pair at a point whereby there is no mixing of the low frequency and voice-frequency currents.

7. In a long distance four wire telephone circuit a trunk exchange provided with a device for the transmission of voice frequency calling and clearing signals comprising a low frequency generator, 5 a voice frequency receiver provided at the end of the incoming pair, means for actuating said low frequency generator by said receiver when receiving voice frequency signals through the incoming pair, a voice frequency generator provided at the end of the outgoing pair, and means for actuating said voice frequency generator by the low frequency generator and for connecting said voice frequency generator in parallel with the outgoing pair in order to transmit voice frequency signals through said outgoing pair from the trunk exchange.

8. In a long distance four wire telephone circuit a trunk exchange provided with a device for the transmission of voice frequency calling and clearing signals, comprising an auxiliary two wire circuit, means for connecting said auxiliary two wire circuit at one end to the trunk exchange and for coupling said circuit at its other end both to the incoming pair and to the outgoing pair of the four wire circuit, a low frequency generator, a voice frequency receiver provided at the end of the incoming pair, means controlled by said receiver whereby said low frequency generator is connected in parallel with said auxiliary two wire circuit when receiving a voice frequency signal through the incoming pair, a voice frequency generator provided at the end of the outgoing pair, means controlled by said low frequency generator whereby said voice frequency generator is connected in parallel with the outgoing pair in order to transmit voice frequency signals through said outgoing pair from the trunk exchange.

9. In a device according to claim 8, a differential transformer for coupling said auxiliary two wire circuit both to the incoming and to the outgoing pairs of the four wire circuit, a filter arranged in the incoming pair, a voice frequency current amplifier connected in parallel to the incoming pair before said filter, a line relay, a chain of relays energized by said amplifier when receiving voice frequency signals through the incoming pair, the last relay of said chain having fixed contacts connected to said line relay and to said low frequency generator respectively and movable armatures connected to said auxiliary two wire circuit in a manner to disconnect said line relay from said auxiliary two wire circuit and to connect said low frequency generator to said circuit when energized by said voice frequency amplifier.
